Howard S. Smith,
HIS ATTORNEY

UNITED STATES PATENT OFFICE.

JOHN GERSTLE, OF DAYTON, OHIO, ASSIGNOR TO THE ELECTRO CHEMICAL COMPANY,
OF DAYTON, OHIO, A CORPORATION OF OHIO.

ELECTROLYTIC CELL.

1,395,704.

Specification of Letters Patent. Patented Nov. 1, 1921.

Application filed December 6, 1920. Serial No. 428,463.

To all whom it may concern:

Be it known that I, JOHN GERSTLE, a citizen of the United States, residing at Dayton, in the county of Montgomery and State 5 of Ohio, have invented certain new and useful Improvements in Electrolytic Cells, of which the following is a specification.

One of the principal objects of my invention is to provide an electrolytic cell whose 10 electrodes can be bodily removed in an easy manner from the electrolytic bath for inspection, cleansing or replacement. The frequent cleansing of the electrodes, which my invention facilitates, is made necessary 15 for the reason that in many electrolytic processes for example for making sodium hypochlorite an insoluble coating of lime is deposited upon the cathode. This deposit must periodically be removed by dipping 20 the electrodes in acid, or the voltage will run up so high on the cell, due to the resistance of the deposit, that its electrical efficiency will be reduced to an uneconomical point.

Another important object of my invention 25 is to raise the plates above the floor of the cell tank. It so happens in electrolytic cells of this type that it is not practical to make the plates taller in proportion when increasing 30 the capacity of the cell. The taller the plates, the greater the density of the hydrogen gas as you go from the bottom up. This gas forms a resistance to the current, and therefore if the area of the plates is increased by making them taller, the amperage 35 consumed will not be in proportion to the added height of them. This means a large increase of electrode material without a proportional increase in the capacity of the cell.

If the capacity of a cell is increased by 40 giving the plates width, the cell tank becomes squat and covers too large a floor space. It is advisable, therefore, when increasing the capacity of a cell, to widen the 45 plates and at the same time raise them off the floor of the cell tank. The narrow space formed by the incasement of the plates, causes the evolved hydrogen gas to pull the liquor upwardly from the bottom of the cell,

50 just as an ascending current of air would do. This incasement is not tight against the electrodes, and does not need to be so, since the hydrogen gas has enough force to carry the liquor beyond the boundary of the in-

casement, and thus causes the proper circulation. 55

Another object of my invention is to provide bus bar connections that are so secured to the plates that they will not touch the electrodes of opposite polarity to short 60 circuit the cell.

It is still another object of my invention to bring the plates close together. The closer together the plates of a cell are the more efficient the process is electrically, since 65 this reduces the resistance of the electrolyte and lowers the voltage; and since the efficiency of a cell depends on the watts of electricity consumed this quantity being the product of the voltage and amperage, the 70 lower the voltage, the more efficient the cell is. By employing non-conducting spacing gaskets, the plates can be brought extremely close together without the mechanical difficulties experienced in placing the electrodes 75 in slots.

Another object of my invention is the provision of means constructed of non-conducting material, for securely holding the plates together. 80

Other important and incidental objects will be brought out in the following specification, and particularly set forth in the subjoined claims.

In the accompanying drawings, Figure 1 85 is an end elevational view of my improved electrolytic cell. Fig. 2 is a side elevation, partly in section, of the same. And Fig. 3 is a top plan view of a series of electrodes connected by my improved means.

Throughout the specification and drawings similar reference characters denote corresponding parts.

Referring to the accompanying drawings, the numeral 1 designates a cell tank preferably constructed of non-conducting material such as soapstone. Mounted on the floor of the tank 1 is a circulation incasement 2 preferably constructed of non-conducting material and provided in its preferably flaring base with circulation holes 3 through which the brine 4 is adapted to enter its hollow interior. 95

Secured within the middle portion of the incasement 2 is a support 5 for a series of electrodes 1^a, 2^a and 3^a. These electrodes, of which 1^a and 3^a may be the anodes and 2 the cathode, are preferably constructed of 105

graphite. These electrodes are preferably connected together at their bottom and upper middle portions by tie-rods 6 and nuts 7 made of non-conducting material. The electrodes are spaced apart by gaskets 8 constructed of non-conducting material such as rubber. These gaskets surround the tie rods 6 between the electrodes, to accurately space the latter.

- 10 When electrodes are brought very close together in cells of high amperage, the bus bars must necessarily be quite thick and therefore means must be provided to prevent the bus bar from touching an electrode of opposite polarity to short circuit the cell. The means I employ for avoiding this difficulty will now be described. It will be noted from Figs. 1 and 2 that the cathode 2^a projects well above the anodes 1^a and 3^a.
15 Secured to each side of the top portion of the cathode by rods 10 and nuts 11, is a transverse metallic member 9. One of these members is connected by a rod 12 and nuts 13, to a bus bar 14 that runs at right angles 20 to said members 9 above the anodes 1^a and 3^a. Accordingly, there is no danger of the transverse members 9 and the bus bar 14 touching the anodes 1^a and 3^a to short circuit the cell.
25 The top front edge of the cathode 2^a is cut away or notched above the shoulder 15 to provide a preferably right-angled recess which clears the following means for connecting the anodes 1^a and 3^a in the electrical 30 circuit. The top outer edge of each anode is gripped by two vertical metallic members 16 which are firmly secured to said anode by rods 17 and nuts 18. One of these vertical members 16 on each anode is secured by 35 rods 19 and nuts 20 to a bus bar 21 which runs at right angles to said vertical members in the same direction as the bus bar 14. The recessed portion of the cathode 2 is of 40 sufficient width and depth to prevent these vertical members 16 and the bus bar 21 from touching it to short circuit the cell. It is thus seen that no matter how close the electrodes are secured together, the bus bars 14 and 21 and the connecting members 9 45 and 16 will not touch the electrodes of opposite polarity to short circuit the cell. In Fig. 3 I have shown a number of electrodes connected together in this way. It is thus possible to employ any number of electrodes 50 compactly connected together in a single cell without danger of short circuiting it. It will also be seen that by the use of my non-conducting gaskets 8 and the bus bar

connections just described, my plates may be brought extremely close together to increase the efficiency of the cell. 60

Holes 22 are preferably provided in the upper portions of the side electrodes 1^a and 3^a. These holes and the space between the electrodes allow the hydrogen gas evolved to 65 circulate the electrolyte so that no outside means are necessary for this purpose.

Having described my invention, I claim:

1. In an electrolytic cell, the combination with spaced-apart electrodes, of supporting 70 means therefor mounted on the floor of the cell, through which the electrolyte can pass to the space between said electrodes.

2. In an electrolytic cell, the combination with spaced-apart electrodes, of a hollow 75 incasement mounted on the floor of the cell for supporting said electrodes, said incasement having openings in its base portion to admit the electrolyte for passage 80 through it to the space between the electrodes.

3. In an electrolytic cell, the combination with an inner and two outer electrodes disposed closely together, the inner electrode projecting above the two outer ones, a pair of 85 transverse metallic members connected to the top side faces of the inner electrode, a bus bar connected to one of said transverse members above and out of contact 90 with the outer electrodes, a pair of vertical transverse metallic members connected to the top side faces of each outer electrode beyond the vertical edge, and above the horizontal edge, of a recess formed in the inner electrode, and a bus bar connected to one 95 of each pair of vertical members, said bus bar passing through the recess in the inner member transversely to, and out of contact with, the latter.

4. In an electrolytic cell, the combination 100 with electrodes, of tie rods and nuts of non-conducting material for connecting said electrodes together, and spacing gaskets of non-conducting material surrounding said tie rods between the electrodes. 105

5. In an electrolytic cell, the combination with a base for the latter, and an electrode unit supported by said base and adapted to be lifted bodily from said base for the 110 purpose specified.

In testimony whereof I have hereunto set my hand this 3rd day of December, 1920.

JOHN GERSTLE.

Witness:

HOWARD S. SMITH.
